DESIGN FOR A STANDARD FOR PERMANENT WAVE APPARATUS

William Martin, Los Angeles, Calif., assignor to
Rilling-Arnao Company, Minneapolis, Minn.,
a corporation of Minnesota

Application November 8, 1935, Serial No. 59,449

Term of patent 3½ years

To all whom it may concern:

Be it known that I, William Martin, a citizen of the United States, residing at Los Angeles, in the county of Los Angeles and State of California, have invented a new, original, and ornamental Design for a Standard for Permanent Wave Apparatus, of which the following is a specification, reference being had to the accompanying drawing, forming part thereof.

The figure is a perspective view of a standard for permanent wave apparatus, showing my new design.

I claim:

The ornamental design for a standard for permanent wave apparatus, as shown.

WM. MARTIN.
